UNITED STATES PATENT OFFICE.

ADAM LOCHNER, OF JEFFERSON CITY, MISSOURI.

KEYLESS LOCK.

No. 841,797.

Specification of Letters Patent.

Patented Jan. 22, 1907.

Application filed July 10, 1906. Serial No. 325,522.

To all whom it may concern:

Be it known that I, ADAM LOCHNER, a citizen of the United States, residing at Jefferson City, in the county of Cole and State of Missouri, have invented a new and useful Keyless Lock, of which the following is a specification.

This invention has relation to keyless locks; and it consists in the novel construction and arrangement of its parts, as herein-after shown and described.

The object of the invention is to provide a keyless lock of simple and durable construction.

15 The lock is adapted to be embedded in a door or other swinging member and is provided with knobs which are located on the opposite sides of the door. The said knobs are attached to shafts, one of which is fixed 20 to a laterally-extending arm, which is adapted to be swung so as to hold the bolts in withdrawn position. Two bolts are provided, and means for guiding the longitudinal movement of the bolts is located within the casing. 25 The shaft of the other knob is provided with a catch, which is adapted to be turned and receive a lug located upon the said arm. Said catch is mounted upon a disk, and adjacent to the said disk is located a notched circular guide. The catch extends almost all 30 of the way around the edge of said guide, and the said lug is adapted to pass through the open space in the catch and enter the notch of the guide, when the catch may be swung over the same and retain the said lug in 35 locked position. When this is done, the end of the bolt-controlling arm is so located that the bolts are in extended positions. Suitable dials are provided over which the knobs are 40 turned, and the said dials are provided with characters from which suitable combinations may be chosen for the purpose of moving the said arm so that it will withdraw the bolts.

In the accompanying drawings, Figure 1 is 45 a side elevation of the lock mechanism with the side of the casing removed. Fig. 2 is an elevation of the opposite side of the lock mechanism with the side of the lock removed. Fig. 3 is a longitudinal sectional view of the 50 lock. Fig. 4 is a side elevation of a dial-plate and knobs.

The lock consists of the casing 1, in the end of which is located the longitudinal movable bolts 2 2. The cross-bar 3 is located within 55 the casing 1 and at an intermediate point is provided with the arc-shaped portion 4.

The inner ends of the bolts 2 2 enter the parallel guides 5, which are located in the fixed plate 6. The shaft 7 extends transversely through the casing 1 and is provided at its 60 ends with the knobs 8 8. The disk 9 is located upon the shaft 7 and is provided with the laterally-extending arm 10, which in turn is provided with a flange 11. The lug 12 is located upon the disk 9. The circular plate 65 13 is attached to the casing 1. The space 14 is provided between the periphery of the plate 13 and the edge of the plate 6. The recess 15 is provided in the periphery of the plate 13 and is located in alignment with the 70 longitudinal axis of the cut-away portion 16 of the plate 9. The said cut-away portion 16 is disposed in the arc of a circle the center of which is the center of the shaft 17.

The shaft 17 is journaled in the casing 1 75 and extends transversely and concentrically through the plate 13. The disk 18 is attached to the shaft 17, and the catch 19 is attached to the said disk 18. The said catch 19 consists of a wire rod which extends out from the 80 disk 18 and passes down along the edge of the plate 13, as at 20. The rod then passes around the said plate 13 and through the space 14 and terminates at a point short of the portion 20. The said rod 19 is adapted 85 to be moved so that the opening between the portion 20 and the end thereof may be brought into register with the recess 15 of the plate 13, and when this is the case the lug 12 may be turned into the said recess 15 or 90 moved out of the same. When the opening between the portion 20 and the end of the said rod 19 does not register with the said recess 15, the lug 12 cannot move into the said recess or move out of the same, for the reason that 95 in attempting to enter or move out of the said recess it will come in contact laterally with the said rod. When the lug 12 is moved into the recess 15, the flange end 11 of the arm 10 is located beyond the end of the arc portion 100 4 of the cross-bar 3, and consequently the bolts 2 2 are in extended position, the coil-springs 21 21 being operatively connected with said bolts to force them in extended position. 105

The outward movement of the bolts 2 is limited by the cross-bar 22, which is provided with perforations that receive the said bolts 2, which is adapted to come in contact with the inner surface of the end of the casing 110 1. When the lug 12 is moved to the end of the cut-away portion 16 of the plate 6, the

flanged end 11 of the arm 10 is moved beyond the opposite end of the arc portion 4 of the cross-bar 3. Consequently the bolts 22 are in extended positions. When, however, the 5 lug 12 is moved to a point intermediate the ends of the recess 15 and the shoulder at the end of the cut-away portion 16, the flange 11 of the arm 10 passes behind the intermediate portion of the arc 4 of the cross-bar 3, and the 10 said bar 3 and its attachments are withdrawn against the tension of the coil-springs 21 21. In this way the bolts 22 are withdrawn.

From the foregoing description it is obvious that even should the space between the 15 portion 20 and the end of the rod 19 be brought into register with the recess 15 the shaft 7 must be properly turned in order to withdraw the bolts 22 and that unless the said space at the end of the rod 19 is brought 20 into register with the recess 15 when the lug 12 is in the said recess the bolts 22 cannot be withdrawn.

The knobs 8 8 and 23 23 are provided with suitable indicating-arrows 24, which may be 25 turned toward any of the characters in the dials 25. The dial-plates 26 are attached to the outer sides of the door and are located under the said knobs.

Having described my invention, what I 30 claim as new, and desire to secure by Letters Patent, is—

1. A keyless lock consisting of a casing, a bolt slidably located in the casing, a shaft extending transversely through the casing, an 35 arm attached to said shaft and adapted to engage the bolt to hold the same in withdrawn position, a lug attached to the shaft, a plate having a recess adapted to receive said lug, and a rotatable member adapted to 40 move over said lug to retain the same in said recess.

2. A keyless lock consisting of a casing, a bolt slidably located therein, a rotatable shaft carrying means for engaging and disengaging 45 the bolt and having an attachment provided with a lug, a recessed plate located in the casing and adapted to receive said lug, a rotata-

ble shaft passing through said plate, and carrying attachments which are adapted to pass over the said lug and retain the same in said 50 recess.

3. A keyless lock consisting of a casing, a bolt slidably located in said casing, a plate having a recess which serves as a guide for the bolt, said plate having a cut-away portion, a shaft rotatably located in the casing, said shaft having a means provided with a lug, and an extending arm, said arm being adapted to engage the bolt and hold the same in withdrawn position, said lug being adapted 60 to move at the cut-away portion of said plate, a second plate located within the casing in proximity to the first said plate, said second plate having a recess located opposite the cut-away portion of the first said plate, a shaft 65 passing through the second said plate, and means carried by said shaft for retaining the said lug in the recess of the second said plate.

4. A keyless lock consisting of a plurality of bolts, a casing receiving the same, springs 70 actuating said bolts, a cross-bar attached to the bolts and having an intermediate arc portion, a rotatable shaft-carrying means adapted to engage the arc portion of said bar and hold the bolts in withdrawn position. 75

5. A keyless lock consisting of a casing, bolts slidably located therein, means connected with the bolts and maintaining the same normally in extended position, a shaft journaled in the casing, a carrying means for 80 withdrawing the bolts, said means having a lug, a plate having a recess adapted to receive said lug, a second shaft journaled in the casing, and a carrying means adapted to be moved over said lug and retain the same 85 within the recess of said plate.

In testimony that I claim the foregoing as my own I have hereto affixed my signature in the presence of two witnesses.

ADAM LOCHNER.
